FRED W. DOLL, OF ALLENTOWN, PENNSYLVANIA, ASSIGNOR OF ONE-HALF TO A. H. BALLIET, OF ALLENTOWN, PENNSYLVANIA.

PUZZLE.

1,114,125.

Specification of Letters Patent. Patented Oct. 20, 1914.

Application filed April 30, 1914. Serial No. 835,339.

To all whom it may concern:

Be it known that I, FRED W. DOLL, a citizen of the United States, residing at 1426 Liberty street, Allentown, in the county of 5 Lehigh and State of Pennsylvania, have invented a certain new and useful Puzzle, of which the following is a specification.

My invention relates to a type of puzzles in which a certain path must be followed by a quantity of mercury, either as a unit or in variously divided portions, and in which certain requirements must be met as to the position of the mercury at certain parts of the journey. It adopts a configuration likened to the Panama Canal and various related lakes and passages and requires transmission of a quantity of mercury from a pool or compartment at one side of the puzzle, indicated as the Atlantic Ocean, 10 to a pool or compartment upon the other side, indicated as the Pacific, or vice versa.

The purposes of my invention are to protect the walls about the terminals of the "canal" out into the respective oceans, so 15 as to require that the mercury be admitted to them in finely divided parts, to place opposing walls conveniently near to the canal terminals so that the mercury may be split up by impact with these opposing walls and 20 caused to rebound into the terminals, to establish a relation between the total quantity of mercury and the capacities of certain pools between the oceans, called lakes, here located on opposite sides of the general line of the canal and to have the sections of the passage near to the entrances to 25 and exits from the lakes slope somewhat in the direction from which the mercury to fill them is supposed to be brought.

40 I have preferred to illustrate my invention by but one form thereof which presents the principles of my invention to the best advantage.

Figure 1 is a top plan view of the preferred form of my invention. Fig. 2 is a section taken upon line 2—2 of Fig. 1.

Similar numerals of reference indicate like parts in the drawing.

The numeral 1 represents the pool named 50 the Atlantic, 2 the Pacific and 3 the isthmus of land lying between, in the immediate vicinity of the canal.

4 is an island in the Atlantic, causing interference with the path of the mercury.

55 The terminal 5, affording an entrance to

the passageway or "canal" 6 is made within a projection or cape 7 of the land which is made convex in order that no considerable quantity of mercury may be balanced at the entrance but that, instead, the mercury may 60 roll around the point of the cape or be cut in two by it without starting within the entrance 5.

The canal 6 follows a tortuous path and comprises a number of sections of which 65 the first, 8, leads past the Gatun Locks and a blind inlet 9, entering the pool or lake 10, marked Gatun Lake, at 11. Under the rules of the puzzle the Gatun Lake, upon one side of the canal, is to be filled with mercury 70 as the mercury is moved from the Atlantic toward the Pacific, and certain other lakes on the opposite side of the canal are to be filled during the reverse movement of the mercury. With this in mind there is some 75 advantage obtained by having the final part of this section 8 slope generally from the Atlantic toward the lake.

The Gatun Lake is intended to have a capacity approximately equal to the entire 80 quantity of mercury contained in the puzzle.

From Gatun Lake the mercury is intended to go through opening 12 into the section 13 of the canal, which slopes also generally toward the terminal 5, from which the mercury is now coming. From a point 14 an inlet 15 leads to pool or lake 16 through opening 17. The canal continues from the point 14 along section 18 of the canal past a blind inlet 19. From the point 20 an inlet 21 leads to a pool or lake 22. The mercury is sufficient in quantity to fill or approximately fill both lakes 16 and 22, and it will be noted that the greater part of each of the inlets leading into these lakes slopes generally from the Pacific entrance toward these lakes, as they are to be filled by mercury coming from the Pacific. The canal continues from point 20 through section 23 to the Pacific which it enters through terminal 100 24 in a projecting piece of land 25 which is also likened to a cape. This presents the same difficulty to mercury entrance presented by the cape entrance on the Atlantic side.

In order that the mercury may be split up 105 readily and make to rebound against the coast near the two canal terminals, I form the outer Atlantic and Pacific boundaries appropriately at 26 and 27, opposite to the two capes and near enough to them for the 110

purpose. The problem is, with the conditions attached, to feed all of the mercury from the Atlantic to the Pacific and then back again.

5 In order that the puzzle may be presented in practical shape, it is put in the form of a box, which I have shown as having a back 28, ends 29, which form the walls 26 and 27, and sides 30. The top is closed by a glass 10 cover 31.

The filling material in the puzzle forming the isthmus 3, is intended to occupy all of the space from the back of the box to the glass in order to avoid passage of the mercury by any other route than that which has 15 been indicated.

It will be observed that the projection of the terminals of the passage into the oceans 20 prevents cornering the mercury about either terminals and getting it started through in a body, which could be done if the terminals were in an indented or "coved" portion of the coast. With the construction shown, the effect of the projecting portions of land at 7 25 and 25 is to divide any considerable body of mercury brought against them, so that none of the mercury enters and to require the splitting up of the mercury into small globules, ordinarily by shaking the puzzle, before any of it can be made to enter either of 30 the terminals 5 and 24. Unless constrained by side walls the contour of any body of mercury will be circular. Partly for this reason, even when but a small part of the 35 mercury is left in either ocean, this small part, unless it be of diameter substantially equaling the width of the terminals or mouths, or smaller, must be broken up into smaller globules before it will enter the 40 canal.

It will be seen that the lakes to be filled lie at some distance to one side or the other of the line joining the terminals 5 and 24, and of the general line of the passage from 45 coast to coast, permitting some shaking of the mercury in either direction without jarring the mercury far enough out of the lake or lakes to be filled to cause this mercury to enter the continuation of the canal toward 50 the coast in whose direction the mercury is being led.

It will be evident that the purposes of my invention do not require that the so-called "canal" pass from one large pool to another, 55 but are, many of them, attained where but a single pool is used and a passage or canal leads out of it.

It will be evident that the path indicated need not be followed to bring a structure 60 within the scope of my claims.

Having thus described my invention, what I claim as new and desire to secure by Letters Patent is:—

1. In game apparatus, a pair of spaced 65 relatively large pools, a body of mercury to

be transmitted from one pool to the other, a spacing between the pools having a tortuous passage through it from one of the large pools to the other and a smaller pool within the spacing body communicating with the passage, and lying a considerable distance to one side of a line joining the points of communication of the passage with the two large pools. 70

2. In game apparatus, a pool representing 75 water, a material bounding the same representing land and having a canal through a portion of the land communicating with the pool through a small opening, a projecting land portion causing the canal terminal to project into the pool, the coast outlined being there convex and a quantity of mercury intended to be passed into said canal. 80

3. In game apparatus, a pair of spaced 85 pools representing water, a volume of mercury in one of said pools and a spacing material representing land projecting outwardly into each pool having a canal there-through communicating with each pool through the land projection therein and a 90 smaller pool between the large pools communicating with the canal and corresponding substantially in capacity to the volume of mercury. 95

4. In game apparatus, a pair of spaced 100 pools representing water, mercury in one of said pools and spacing material between the pools having a passage therebetween forming a communication between the pools and having storage space on each side of a line 100 between the terminals of the passage representing lakes and corresponding substantially to the quantity of mercury used and communicating with the passage. 105

5. In game apparatus, a pair of spaced 110 pools representing the Atlantic and Pacific Oceans, a spacing material between representing an isthmus and having a passage through it from ocean to ocean to represent the Panama Canal with spaces communicating with the passage representing lakes located on opposite sides of the canal and a volume of mercury substantially corresponding in size to the content of one of these lakes. 115

6. In game apparatus, a pair of spaced 120 pools representing the Atlantic and Pacific Oceans, a volume of mercury in one of the pools and a spacing material between representing an isthmus and having a passage 125 through it from ocean to ocean to represent the Panama Canal with spaces communicating with the passage representing lakes located on opposite sides of the canal and providing storage for substantially all of the 125 mercury upon each side of the passage. 130

7. In a game apparatus, a pair of spaced pools corresponding to the Atlantic and Pacific Oceans, and a spacing material corresponding to the Isthmus of Panama project- 130

ing into both oceans in cape like formation and having a canal through the isthmus terminating in the capes in combination with a considerable quantity of mercury to be 5 passed through the canal.

8. In game apparatus, a pool adapted to contain mercury and a boundary material therefor projecting into the pool in cape like formation and having a passage through 10 the cape communicating with the pool substantially at the end of the cape and having a narrow opening in combination with a body of mercury in the pool greatly in excess 15 in diameter of the size of the passage opening.

9. In game apparatus, a pool adapted to contain mercury and a boundary material therefor projecting into the pool in cape like formation and having a passage through the cape communicating with the pool substantially 20 at the end of the cape and having a narrow opening in combination with a second boundary across the opening and in proximity thereto and a body of mercury in the pool greatly in excess in diameter of the 25 size of the passage opening.
